Philip Lawrence Rice Kennedy

UNITED STATES PATENT OFFICE.

JOHN A. LE CAIN, OF MALDEN, MASSACHUSETTS, ASSIGNOR TO WORTHINGTON PUMP AND MACHINERY CORPORATION, A CORPORATION OF VIRGINIA.

VALVE.

1,405,525.

Specification of Letters Patent.

Patented Feb. 7, 1923.

Application filed September 14, 1920. Serial No. 410,110.

To all whom it may concern:

Be it known that I, JOHN A. LE CAIN, a citizen of the United States, residing at Malden, county of Middlesex, and State of Massachusetts, have invented certain new and useful Improvements in Valves, fully described and represented in the following specification and the accompanying drawings, forming a part of the same.

10 This invention relates to improvements in valves for pumps, compressors or the like, and relates especially to a valve service of the type in which the suction and discharge valves are arranged in line and are readily removable as a unit and detachable for adjustments and replacements or for insertion of a substitute service with a minimum of delay.

In such valve services, it has been necessary that the machined holes through the valve decks which receive the valve seats be carefully aligned and that the facings of the valve decks against which the valve seats bear be parallel, and one important feature 25 of the invention is the provision of a cheap, compact and efficient valve service in which the careful aligning of the valve seats and the paralleling of the valve deck facings is unnecessary.

30 In the accompanying drawing forming a part of this specification, a vertical section of a valve service embodying all the features of the invention in their preferred form is shown, and this construction will now be described in detail and the features forming the invention then specifically pointed out in the claims.

Referring to the drawing, valve chamber A, which is closed by cover B, is provided 40 with suction and discharge valve decks 10, 11 which receive, respectively, the suction and discharge valve seats 12, 13, the suction valve seat 12 being secured in deck 10 in any suitable manner as by driving in on the taper. Suitable suction and discharge valves 14, 15, preferably of the form shown 45 comprising one or more annular plates 1, seat respectively against the suction and discharge valve seats 12, 13, the discharge valve 15 being guided by a guide 16 having screw threaded ends 17, 18 engaging, respectively, the discharge valve seat 13 and

5 a valve guard 19, against which the discharge valve spring 20 bears. A suction valve guard 23, against which suction valve 55 spring 24 bears, is secured to the discharge valve seat 13, as by casting integrally therewith, and is provided with a recessed or hollow portion 2.

One of the important features of my invention consists in providing a guide for the suction valve such that the suction valve will seat and be properly guided even though the suction and discharge ports are not in exact alignment and the valve deck 65 facings are not exactly parallel. This result is secured by mounting the valve guide loosely so as to have a slight play, and preferably it is of the form shown in which suction valve 14 is guided by a guide 3 70 which extends into and fits somewhat loosely within the hollow portion 2 of the suction valve guard 23 and is loosely secured thereto as by cotter pin 4 passing through holes 5 in the suction valve guard 23, and hole 6 75 in the suction valve guide 3. In order that the service may be removed as a unit, the lower end of the valve guide 3, which fits loosely within a recess 7 in the suction valve seat 12, is preferably formed with a head 8 80 adapted to engage and remove the suction valve 14 with the other parts, so that the entire valve service is assembled and disassembled on the bench, as is most convenient. The suction valve guard, therefore, 85 is fixed to the discharge valve seat and withdrawn with it, although there is no rigid connection between the discharge valve seat and the suction valve guide or seat.

90 While the construction shown in connection with the suction valve is of especial value in combination with another valve in line therewith, and such combination forms a part of the invention, it will be understood that this construction is applicable 95 also to a single valve, either suction or discharge, independently of its relation to other valves, and certain features of this construction are thus broadly claimed.

100 Suitable means are provided for holding the valve service in position, which may advantageously be of the form shown in which a heavy spring 21 bears against the discharge valve guard 19 and cover B and is

held in position by a projection 22 on the cover B extending nearly to the valve guard 19.

Leakage is reduced to a minimum as the present construction does not use a binding screw above the valve service or a holding bolt passing through the bottom of the valve chamber, and for the same reason a minimum of time is required for the removal of the valve service as it is only necessary to remove the cover for access to and removal of the valve service. The omission of the binding screw for holding the service in place avoids, also, the difficulty in adjusting the binding screw accurately.

There is no danger of the parts coming adrift as the discharge valve guard, guide and seat are securely held by the heavy spring which holds the whole valve service in position, and upon failure of this spring for any reason the parts are held by contact between the discharge valve guard and the projection 22 on cover B. The suction valve bolt is held by the cotter pin so that there is no chance of it coming free from the suction valve guard, and the latter is fixed to the discharge valve seat, preferably a part of the discharge valve seat casting, as shown. There is no tendency of the removable discharge valve seat to loosen the suction valve seat as the suction valve guard and guide connected to the discharge valve seat are not rigidly connected to the suction valve seat. The discharge valve seat, therefore, may have a loose fit in the deck, so as to be readily withdrawn and leakage between the valve seat and deck prevented by the metal to metal ground joint between the top of the valve deck and the underside of the valve seat flange.

While the construction shown and described is a preferred embodiment of my invention, it will be understood that many modifications may be made therein within the invention as defined by the claims.

What is claimed is:

1. A valve structure having a plurality of valve seats in line, valves on the seats, and a loosely mounted guide for one of the valves.

2. A valve service having suction and discharge valve seats in line, valves on the seats, and a loosely mounted guide for one of the valves.

3. A valve service having suction and discharge valve seats in line, valves on the seats, a suction valve guard fixed to the discharge valve seat, and a loosely mounted guide for the suction valve connected to the discharge valve seat.

4. A valve service having suction and discharge valve seats in line, valves on the seats, a loosely mounted guide for the suction valve connected to the discharge valve

seat, and means on the guide for removal of the suction valve with the discharge valve and its seat as a unit.

5. A valve service having suction and discharge valve seats in line, valves on the seats, connections between the valves and discharge valve seat whereby these parts may be removed as a unit, and resilient means for holding the discharge valve seat and connected parts in place.

6. A valve service having suction and discharge valve seats in line, valves on the seats, connections between the valves and the discharge valve seat whereby these parts may be removed as a unit, a spring for holding the discharge valve seat and connected parts in place, and a cap for holding the spring and formed to prevent floating of the discharge valve seat upon failure of the spring.

7. A valve service having suction and discharge valve seats in line, valves on the seats, a loosely mounted guide for the suction valve connected to the discharge valve seat and resilient means for holding the parts in place.

8. A valve service having suction and discharge valve seats in line, valves on the seats, a loosely mounted guide for the suction valve connected to the discharge valve seat, means on the guide for removal of the suction valve with the discharge valve and its seat as a unit, and resilient means for holding the discharge valve seat and connected parts in place.

9. A valve service having suction and discharge valve seats in line, valves on the seats, guards and valve springs for the valves, the suction valve guard being fixed to the discharge valve seat, and a guide for the suction valve loosely secured to the suction valve guard.

10. A valve service having suction and discharge valve seats in line, valves on the seats, guards and valve springs for the valves, the suction valve guard being fixed to the discharge valve seat and a guide for the suction valve loosely secured to the suction valve guard and adapted to remove the suction valve with the discharge valve seat and its valve as a unit.

11. A valve service having suction and discharge valve seats and valves in line, the discharge valve seat being free from its valve deck, and a connection between the discharge valve seat and suction valve for removing the latter with the discharge valve seat independently of the suction valve seat.

12. A valve service having suction and discharge valve seats and valves in line, the discharge valve seat being free for removal from its valve deck and the suction valve seat fixed in its valve deck, and a valve guide for the suction valve connected to the discharge valve seat but loosely mounted to

permit the valve seats to be somewhat out of alignment and parallelism.

13. A valve structure comprising a valve seat, a valve thereon, and a loosely mounted 5 stationary guide for the valve.

14. A valve structure comprising a valve seat, a valve thereon, a guard for the valve independent of the seat, and a stationary 10 guide for the valve loosely mounted on the guard.

15. A valve structure comprising a valve seat, a valve thereon, a guard for the valve independent of the seat, a guide for the valve loosely mounted on the guard, and 15 means for removal of the valve with the guard independently of the seat.

16. The combination with a fixed valve seat and its valve, of valve guard 23 independent thereof and formed with a recess 2, 20 valve guide 3 fitting loosely within the recess, and a non-rigid connection between guide 3 and guard 23.

17. The combination with a fixed valve seat and its valve, of valve guard 23 independent thereof and formed with a recess 2, 25 recess 7 in the fixed valve seat, valve guide

3 fitting loosely within the recesses 2 and 7, a non-rigid connection between guide 3 and guard 23, and head 8 on guide 3 for removal of the valve with guide 3 and guard 23. 30

18. The combination with a fixed valve seat, a valve seat free for removal from its valve deck, and valves on the seats, of valve guard 23 fixed to the free valve seat and formed with a recess 2, valve guide 3 fitting 35 loosely within the recess, and a non-rigid connection between guide 3 and guard 23.

19. The combination with a fixed valve seat, a valve seat free for removal from its valve deck, and valves on the seats, of valve 40 guard 23 fixed to the free valve seat and formed with a recess 2, recess 7 in the fixed valve seat, valve guide 3 fitting loosely within the recesses 2 and 7, a non-rigid connection between guide 3 and guard 23 comprising 45 cotter pin 4 passing through the guard 23, and head 8 on guide 3 for removal of the other valve with the free valve seat and its valve.

In testimony whereof, I have hereunto set 50 my hand.

JOHN A. LE CAIN.
